AMUSEMENT DEVICE

Arvid Dahlstrom and Peter N. Nelson, Chicago,
Ill., assignors, by mesne assignments, to Albert
J. Tarrson, Edward A. Cohan, and James E.
Johnson, all of Chicago, Ill.

Application November 7, 1934, Serial No. 751,832

16 Claims. (Cl. 194—9)

This invention relates to an amusement device and more particularly to a coin controlled target game in which suitable space charges, preferably balls or the like, may be projected from a pistol or other propelling means directed at an intermittently exposed target.

The embodiment herein illustrated and described comprises a coin controlled mechanism including a repeating pistol and an automatically operable target mechanism. The target mechanism comprises a fixed target capable of electrically setting up a score on a scoring device each time the target is hit by a projectile. The target is intermittently exposed by means of a moving disk positioned in front of the target and having holes therethrough which are consecutively moved past the target, thus requiring considerable skill on the part of the player in operating the pistol in synchronism with the exposure of the target.

In the present embodiment the balls or projectiles, after being shot, roll back down an inclined plane and are automatically received by the pistol, and the pistol may be repeatedly fired only during a predetermined time interval which interval is determined by a suitable coin controlled mechanism. At the expiration of the predetermined time period, the target and scoring mechanism, as well as the pistol, become ineffective for further operation until another coin has been inserted.

It is an object of the present invention to provide a coin controlled target game in which an automatically reloading pistol may be continually fired as long as the mechanism is in operation, or, in other words, during a predetermined time period limited by the operation of the coin controlled mechanism.

A further object is the provision of a target mechanism, particularly in combination with a projectile propelling device, in which the target is intermittently exposed and in which the striking of the target will automatically set up a corresponding score.

A further object is the provision of a coin controlled target game having a pistol or projector and in which the projectiles are automatically returned from the target in a manner to automatically reload the pistol, and in which the pistol is ineffective for further operation after a predetermined time period and until the insertion of another coin.

A desirable feature is the construction of the device in widely separated units or sub-assemblies which are electrically connected for mutual

cooperation, and in which each unit may be readily removed without disturbing another by merely separating the electrical connections.

Further objects will be apparent from the specification and the appended claims. 5

In the drawings:

Figure 1 is a perspective view of the entire assembled device, a portion of the casing being broken away for purposes of illustration.

Fig. 2 is a fragmentary side elevation of the pistol with the chute for returning the balls to the pistol illustrated in longitudinal section.

Fig. 3 is a transverse section through the reloading portion of the pistol and chute, and taken on a line substantially corresponding to line 3—3 15 of Fig. 2.

Fig. 4 is a longitudinal section through the embodiment illustrated in Fig. 1, and taken on a line substantially corresponding to line 4—4 of Fig. 1. 20

Fig. 5 is a transverse section taken on a line substantially corresponding to line 5—5 of Fig. 4 and illustrates the coin receiving and pistol control mechanism, all of which are mounted on the front plate of the device. 25

Fig. 6 is a vertical section through the coin receiving slot and associated mechanism, and taken on a line substantially corresponding to line 6—6 of Fig. 5.

Fig. 7 is a vertical section through the motor switch control, and taken on a line substantially corresponding to line 7—7 of Fig. 5. 30

Fig. 8 is a transverse sectional view taken on a line substantially corresponding to line 8—8 of Fig. 4, and is a back view of the motor and target control mechanism and the score mechanism associated therewith. 35

Fig. 9 is a top view of the mechanism illustrated in Fig. 8.

Fig. 10 is a detail back view, partially in section, of the motor transmission to the target cover and the time control wheel forming a part of the transmission. 40

Fig. 11 is a bottom view of the mechanism illustrated in Fig. 10 including the switch control mechanism associated therewith. 45

Fig. 12 is a diagrammatic view of the wiring and switches and a portion of the associated mechanism.

Referring to the drawings in detail, the embodiment illustrated comprises a casing 1 having a coin receiving mechanism and a projectile propelling device at the front end of the casing, and a target mechanism and scoring device at the opposite end. These units are not mechanically 50 55

connected but are electrically associated for mutual cooperation.

The unit or sub-assembly at the front of the structure comprises a plate 2 mounted on the front wall of the casing as illustrated in Figs. 1, 4 and 5 and includes a pistol 3 which is pivotally mounted on the plate at 4 and extends therethrough. In the present embodiment, the pistol is mounted for slight vertical oscillation only. 5 The plate 2 is provided with a window 5 through which the target may be observed and is also provided with a coin slot 6 and an elongated coin window 7. Referring particularly to Fig. 4, the pistol 3 preferably comprises a longitudinally 10 split casing, the two halves of which may be secured together in any suitable manner, the entire pistol being pivoted at 4.

The pistol is provided with an angular barrel or bore 8 which terminates in an arcuate portion 9 for the purpose of directing the projectile into alignment with the upper surface of the pistol. The pistol is provided with a side opening 10 arranged to receive consecutive projectiles from a chute 11 secured to the front plate 2 and which 15 projects forwardly as illustrated in Fig. 2 and in a position to receive the projectiles 12 as they return by gravity down the incline plate 13, which latter extends forwardly from the target. This plate is provided with a hole 14 located over 20 the forward end of the chute 11. The plate 13 is so formed that a ball placed anywhere thereon will roll through the hole. By this means, the balls 12 will roll out of the incline plate 13 and through the chute 11 and will be automatically 25 received into the barrel of the pistol through the side opening 10, whereby they may be fired therefrom as rapidly as the user operates the trigger.

The pistol is provided with a spring pressed plunger 15 in alignment with the straight portion 40 of the barrel 8 and slidably mounted in lugs 16 and 17. The plunger is normally retained in the forward position illustrated by means of a compression spring 18. A trigger 19 is pivoted at 20 and normally urged to the forward position shown by means of a spring 21. A pawl 22 is pivoted at 25 23 on the trigger 19 and moves therewith during each operation of the trigger.

The plunger 15 is provided with a flange 24 which, during the operation of the machine after 50 the coin has been inserted, may be engaged by a pawl tooth 25 on the pawl 22 when the trigger is pulled rearwardly. Normally, however, the pawl 22 is retained in the raised position shown by means of a bell crank lever 26 pivoted at 27 and having a rearwardly extending arm 28 engaged under a pin 29 on the pawl 22, thereby 55 retaining the pawl 22 in the raised position, and in which position the trigger may be operated but will be ineffective to operate the plunger 15 as the pawl 22 cannot engage the plunger. After 60 a coin has been inserted, the bell crank lever 26 will be moved by mechanism which will be described later, to allow the pawl 22 to be lowered to a position where the tooth 25 may engage the flange 24 and move the plunger rearwardly. During this rearward movement of the plunger 15, one of the balls 12 will roll into the barrel 8 in front of the plunger and a further rearward movement of the trigger will cause the cam-like 65 end of the pawl 22 to engage the pin 30 and raise the pawl, thereby releasing the plunger, and the ball 12 will be projected from the barrel 8 toward the target.

The machine is ordinarily so constructed that 70 when a coin is inserted, the mechanism may then

be operated to make the pistol effective to repeatedly project balls or other suitable space charges therefrom as long as a motor driven mechanism cooperating with the target is in operation. In ordinary practice, the target mechanism is arranged to be in operation for a time period of thirty seconds with each insertion of a coin and the operator may shoot as many balls as possible during that time period.

The coin receiving mechanism is more clearly 10 illustrated in Figs. 5 to 7, inclusive, and comprises a coin chute 31 positioned directly behind the coin window 7 and, in the present instance, is arranged to retain four coins therein as illustrated in Fig. 5. The coin receiving slot 6 communicates with this coin chute and a coin escarpement device is mounted directly back of the coin chute and adjacent the coin slot and comprises a rock-shaft 32 having an escapement member 33 secured thereto. This escapement 15 member is provided with forwardly extending arms 34 and 35 and is normally retained in the position shown in Fig. 6 by means of a spring 36.

The shaft 32 is provided with a downwardly extending arm 37, and a plunger 38 is slidably 20 mounted in the plate 2 in a position to be manually manipulated after the coin has been inserted in the machine. A spring 39 is mounted adjacent the coin chute and provided with an inwardly extending portion 40 which extends into 25 the path of the coins in the chute and normally retains four coins in the position illustrated in Fig. 5. An escapement pawl 41 is pivoted at 42 and provided with an inwardly extending pin 43 which also extends into the path of the coins 30 in the chute 31. The escapement pawl 41 is normally retained in position by means of a spring 41a. The coin controlled mechanism is shown in normal position; that is, when the device is not in operation. The escapement pawl 40 41 normally holds the vertical slide 44 downwardly against the tension of a spring 45 and in the position shown, by means of its engagement in the notch 46.

When it is desired to operate the machine, a 45 coin may be inserted in the coin slot 6 and it will drop to a position where it will rest on the inwardly extending arms 34 of the coin escarpement member 33. The plunger 38 may then be pushed inwardly, thereby oscillating the escapement member and the coin will be released from the arm 34 and the entire row of coins in the chute 31 will be pushed downwardly by means of the arm 35. During the downward movement of the coins, the lowest coin in the chute will 50 force the spring 39 outwardly and will drop into a suitable receptacle below. The next coin, by reason of its engagement with the pin 43 of the escapement pawl 41, will move the pawl to release the vertical slide 44 which will then be 55 raised to the dotted position shown by means of a spring 45.

A rockshaft 47 is mounted in suitable bearings 48 and provided with an arm 49 engaging in a hole in the vertical slide 44. The rockshaft is 60 provided with a link 50 which is connected to the downwardly extending arm of the trigger controlling bell crank 26, previously described, so that as soon as the vertical slide 44 is released 65 the rockshaft will be operated to cause the pawl 22 on the trigger 19 to be released to a position to engage the flange 24 on the plunger 15 when the trigger is operated, whereby the pistol may 70 be repeatedly operated until the slide 44 is re- 75

turned to its normal position by means which will be described later.

The rockshaft 47 is also provided with an upwardly extending flange or arm 51 which is preferably of insulating material and is closely adjacent a main switch for controlling the operation of the motor and which comprises spring contact members 52, as illustrated in Fig. 7, so that when the rockshaft is oscillated by upward movement of the slide 44, the motor switch will be closed and the motor will start simultaneously with the releasing of the trigger mechanism whereby the pistol may be operated as long as the motor continues to run. In order to make the pistol ineffective after a predetermined time period, a solenoid 53 is provided with a pivoted arm 54 connected to the vertical slide 44 by means of a pin and slot connection as illustrated, and when the solenoid 53 is energized at the termination of a predetermined time period, the slide 44 will again be pulled downwardly and retained by the pawl 41 and the entire machine will become ineffective until another coin is inserted.

The target mechanism is particularly illustrated in Figs. 4 and 8 and comprises a target mechanism and a score mechanism assembled in a single unit consisting of a vertical plate 55 having suitable brackets thereon for supporting the mechanism and also having forwardly extending bars 13^a for supporting the inclined floor plate 13. This entire assembly, including the floor 13, may be removed by sliding it rearwardly on the bars or supports 56 which are secured to the sides of the casing and which slidably support the entire unit. The back 57 of the casing is removable whereby the entire target and score assembly, including the inclined floor plate 13, may be removed from the casing as a unit by merely sliding the assembly rearwardly on the slides or guides 56. The only connection between the target mechanism and the coin controlled mechanism at the front of the machine is a set of electric wires interconnecting various electrically controlled devices and these wires may be provided with a suitable connector, not shown, whereby they may be disconnected when it is desired to remove the target unit.

The target mechanism comprises a disk-like target or bull's-eye 58 mounted at the back of a suitable opening 59 in the plate 55. The target is mounted on a plunger portion 60 which is slidably supported in a bracket 61 and insulated therefrom. Spring contacts 62 are mounted at the rear of the plunger 60 and in a position to be closed when the target 58 is struck by one of the projectiles. These contacts are for the purpose of controlling the operation of a scoring mechanism which will be described later.

A rotatable disk 63 is secured to a shaft 64 and is positioned between the plate 55 and the target 58. This rotatable disk is preferably transparent or translucent and is provided with a plurality of holes 64' substantially corresponding in size to the target 58 and movable into alignment therewith, whereby during the rotation of the disk 63 the target 58 will be intermittently exposed. The disk 63 is preferably of a suitable insulating material in common use, similar in appearance to celluloid but having somewhat different characteristics, whereby it is not injured by the impact of the projectiles and is not easily dented or otherwise marred as is the case if metal is used in such a position. The front of the plate 55 is also covered with a sheet 65 of the same material. A motor 66 is mounted at the rear of the plate 55

and provided with a speed reduction transmission for driving the disk 63. This transmission comprises a worm 67 on the motor shaft (Fig. 8) in mesh with a worm wheel 68 on a vertical shaft 69. The shaft 69 is also provided with a worm 70 in mesh with a worm wheel 71 on a shaft 72. A so-called "time gear" 73 is secured to the shaft 72 and is in mesh with a pinion 74 on the disk shaft 64. This transmission is arranged so that during the operation of the mechanism, the time gear 73 preferably rotates once in a time period of thirty seconds. In the embodiment illustrated, the ratio of the time gear to the disk pinion 74 is five to one; therefore, the disk 63 will be rotated five times in thirty seconds and, as the disk 63, in the present embodiment, is provided with four symmetrically positioned target openings, an accurate marksman has the possibility of hitting the target twenty times during the operation of the machine by the insertion of a single coin.

It will be apparent from the previous description that as soon as a coin has been inserted in the coin slot and the slide 38 has been pushed inwardly by the operator, the pistol will immediately be in a condition for repeated operation and simultaneously the motor contacts 52 will be closed and the motor will operate to rotate the time gear one revolution and the disk 63 will be operated accordingly.

In order to stop the entire machine and make the device ineffective after a single revolution of the time gear 73, a cam pin 75 is secured to the gear 73 in a position to engage and move an insulating switch-operating member 76 which is mounted on an arm 77 pivoted at 78 and normally retained in the position illustrated in Fig. 11 by means of a spring 79. This switch operating member 76 is arranged to close two switches 80 and 81 (Fig. 8) in the manner illustrated in Fig. 11.

The operation of the electrical system, including the switches 80 and 81, is diagrammatically illustrated in Fig. 12 in which it will be apparent that when the switch 80 is closed the solenoid 53 at the front of the machine will be immediately operated to pull the vertical slide 44 downwardly to simultaneously open the switch 52 of the motor circuit. However, in order to allow the continued operation of the motor so that the time gear 73 may continue to move sufficiently to release the switch operating member 76 from the cam pin 75, the switch 81, which short circuits the main motor switch, will remain closed until the gear 73 has moved sufficiently to allow the release of the switch operating member 76 from the pin 75 when both of the switches 80 and 81 will be simultaneously opened and the motor will be stopped until another coin has been inserted in the device.

As previously described, the target switch contacts 62 are arranged to be closed by rearward movement of the target when it is struck by the projectiles. The closing of this switch is arranged to energize a solenoid 82 which is arranged to permit the automatic operation of a suitable scoring mechanism. This scoring mechanism is mounted above the target and comprises a score wheel 83 having suitable score legends on its periphery. A portion of this wheel is exposed through an opening in the plate 55 above the target and the wheel is secured to a vertical shaft 84, to which is secured a ratchet wheel 85. The wheel tends to rotate in the direction of the arrow by reason of spring pressure thereon, and an escapement pawl 86 is pivoted at 87 and con-

nected to a movable arm 88 on the solenoid 82 by means of a link 89. It will therefore be apparent that each time the solenoid 82 is energized by reason of the projectile striking the target 58, 5 the escapement dog 86 will operate to release the scoring wheel and consecutive scores may thereby be set up by consecutively striking the target. The score wheel is moved by means of a pinion 90 secured to the shaft 84 and in engagement with 10 a slidable rack 91 (Fig. 8) which is normally retained in the position shown against the tension of a spring 92 so that each time the wheel 83 is released by the solenoid operated escapement 82, the spring 92 will cause a partial rotation of the 15 score wheel by reason of the spring pressed rack and pinion connection.

It is desirable to reset the score wheel 83 simultaneously with or immediately prior to the stopping of the time wheel 73. For this purpose a 20 bell crank lever 93 (Fig. 8) is pivoted at 94 and provided with an upwardly extending arm 95 engaging the end of the rack 91. An inwardly extending arm 96 of this bell crank is positioned to be engaged by a pin 97 on the time gear 73. 25 Therefore, with the insertion of each coin in the device, the time gear 73 will make one revolution and will then reset the score wheel 83 to zero by pushing the rack 91 laterally by means of the bell crank 93 and will also operate the switches 30 80 and 81, whereby all of the mechanism is returned to a normal position for a succeeding operation of the device. A resistance 98 may be included in the motor circuit to provide the desired electrical characteristics, and a fan 99 is 35 secured on the motor shaft for cooling the resistance. A current distributing board 100 may be mounted on the motor supporting bracket and suitable connectors may be secured thereto.

The electrical operation of the device may be 40 easily traced in Fig. 12 in which the electrical arrangement is illustrated in a simplified wiring diagram.

The operation is as follows: When a coin is inserted in the coin slot and the plunger 38 pushed 45 inwardly, the coin escapement pawl 41 will release the slide 44 which will rise and operate the rockshaft 47 to close the motor switch 52. The operation of the motor will then cause the time gear 73 to make one complete revolution. 50 The pistol trigger pawl will simultaneously be released and the pistol may be operated as many times as possible during the predetermined time limited by the rotation of the time wheel. The closing of the switch 62, when the target 58 is 55 hit, will cause the solenoid 82 to be energized, thereby releasing the score wheel 83 and successive operation of the target 58 will cause corresponding successive operation of the score wheel 83 to display a correspondingly increasing 60 score.

A complete revolution of the time gear 73 will cause the cam pin 75 thereon to engage the switch operating block 76 and close the switches 80 and 81. The switch 80 will energize the solenoid 53 and thereby reset the coin controlled mechanism and open the motor switch 52. However, the switch 81 is closed simultaneously with the switch 80 and short circuits the motor switch 65 whereby the motor will remain in operation until the wheel has completed its revolution and the switch operating block 76 is released from the pin 75, whereupon the switches 80 and 81 will again be opened and the entire circuit and the 70 mechanism associated therewith will again be 75

in normal position ready to be again operated upon the insertion of another coin.

Wherever the word pistol is used herein it is intended to mean any suitable means for propelling a space charge capable of affecting a 5 target.

Modifications may be made without departing from the spirit of the invention and it is desired, therefore, that the invention be limited only by the prior art and the scope of the appended 10 claims.

Having thus described the invention, what is desired to be secured by Letters Patent is:

1. In a coin controlled amusement device, a target, a normally inoperative pistol for shooting 15 projectiles at said target, a rotatable shield between said pistol and said target and having radially disposed holes therethrough to intermittently expose said target, means to automatically return projectiles from said target to said pistol, 20 and coin controlled mechanism to make said pistol operative for repeated operation and to simultaneously rotate said shield for a predetermined time period.

2. In an amusement device having a normally 25 ineffective propelling device for balls, a target above the level of said propelling device, an inclined surface for returning the balls into propelling relation with said device, and coin controlled mechanism for making said propelling device 30 continuously effective for manual control to repeatedly propel balls over a predetermined limited time period, automatic means for limiting said time period, and means intermittently blocking the path of said projectiles during said time 35 period.

3. A target game comprising a target, a ball propelling pistol having a spring pressed propelling means, a trigger for operating said propelling means, means normally preventing the 40 trigger operation of said propelling means, an inclined surface positioned to automatically return the balls to propelling position, coin controlled mechanism for making said preventing means ineffective to prevent repeated trigger operation of said propelling means for a predetermined limited time period, and means for automatically resetting said coin controlled mechanism to limit the time period of said repeated 45 operation. 50

4. In an electrically operated coin controlled target game, a normally ineffective projectile propeller, a fixed target, movable means to intermittently expose said target, an electrical circuit including a motor for operating said movable means, a switch for starting said motor, an auxiliary motor switch, coin controlled means for closing said first motor switch and enabling effective operation of said propeller, means for resetting said coin controlled means and simultaneously opening said first motor switch and closing said auxiliary motor switch, and means whereby continued operation of said motor is effective to quickly reopen said auxiliary motor switch. 60 65

5. In a coin controlled amusement device of the character described, a target, a pistol for shooting projectiles at said target, means for intermittently moving a barrier in the path of said projectiles, a motor for operating said means, coin controlled means for controlling all of said elements, a transmission between said motor and said barrier, means movable by said transmission, and electrical means controlled by said movable 70 75

means to limit the coin controlled operating time of said device.

6. In a coin controlled amusement device of the character described, a target, a pistol for shooting projectiles at said target, a cumulative score indicating means, means for intermittently moving a barrier in the path of said projectiles, a motor for operating said means, coin controlled means for controlling all of said elements, a transmission between said motor and said barrier, means movable by said transmission, means controlled by said movable means to reset said score indicating means, and electrical means controlled by said movable means to limit the coin controlled operating time of said device.

7. In an amusement device of the character described, the combination with a normally inoperative pistol constructed and arranged to direct a space charge an indeterminate number of times to affect a target in accordance with the skill of the operator during a predetermined limited time interval, of coin controlled means to make said pistol operative, means for limiting the time of pistol operation, an intermittently exposed target, and automatic means controlled by said target when affected by said space charge to set up cumulative numerical scores during said time interval.

8. An amusement device comprising a target, a pistol for propelling balls toward said target, said pistol having a frame with a normal sighting line parallel with the line of flight of a projectile, an angular barrel or bore extending rearwardly and downwardly from the line of flight and terminating in a lateral opening to receive projectiles, means for applying propelling force in alignment with said angular bore, and a trigger for operating said propelling means.

9. An amusement device comprising a target, a pistol for propelling balls toward said target, said pistol having a frame with a normal sighting line parallel with the line of flight of a projectile, an angular barrel or bore extending rearwardly and downwardly from the line of flight and terminating in a lateral opening to receive projectiles, means for applying propelling force in alignment with said angular bore, a trigger for operating said propelling means, and an inclined surface to return balls from said target into the bore of said pistol.

10. An amusement device comprising a target, a pistol for propelling balls toward said target, said pistol having a frame with a normal sighting line parallel with the line of flight of a projectile, an angular barrel or bore extending rearwardly and downwardly from the line of flight and terminating in a lateral opening to receive projectiles, means for applying propelling force in alignment with said angular bore, a trigger normally ineffective to operate said propelling means, and coin controlled mechanism for making said trigger effective.

11. An amusement device comprising a target, a pistol having a bore for directing projectiles in a predetermined line of flight toward said target, said bore having a portion extending angularly downward from said line of flight, means constructed and arranged to provide an inclined path from said target to cause the projectiles fired at said target to automatically return to firing position in said bore, a projectile propelling means, a trigger normally ineffective to operate said propelling means, and a coin controlled means for making said trigger effective to operate said propelling means.

12. An amusement device comprising a target, a pistol having a bore for directing projectiles in a predetermined line of flight toward said target, said bore having a portion extending angularly downward from said line of flight, means constructed and arranged to provide an inclined path from said target to cause the projectiles fired at said target to automatically return to firing position in said bore, a projectile propelling means, a trigger normally ineffective to operate said propelling means, and a coin controlled means for making said trigger effective to continually operate said propelling means for a predetermined limited time period.

13. An amusement device comprising a target, a pistol having a bore for directing projectiles in a predetermined line of flight toward said target, said bore having a portion extending angularly downward from said line of flight, means constructed and arranged to provide an inclined path from said target to cause the projectiles fired at said target to automatically return to firing position in said bore, a projectile propelling means, a trigger normally ineffective to operate said propelling means, a coin controlled means for making said trigger effective to operate said propelling means, and means preventing a succeeding effective operation of said coin controlled mechanism for a predetermined limited time period.

14. In a target game of the character described the combination with a manually operable projector adapted to materially affect a remote target through the space between said projector and target, and means for preventing the affecting of said target coin controlled mechanism for making said preventing means ineffective, of a target capable of being affected by operation of said projector in accordance with the skill of the operator, a motor, means controlled by said motor for intermittently making said target inaccessible to said projector, a cumulative scoring means operable by said target in accordance with the affecting of said target by the operation of said projector, and means controlled by said motor for resetting said scoring means.

15. In an amusement device of the character described, the combination with a normally inoperative projector constructed and arranged to direct a space charge an indeterminate number of times to affect a target in accordance with the skill of the operator during a predetermined limited time interval, of coin controlled means to make said projector operative, means for limiting the time of projector operation, and automatic means controlled by said target when affected by said space charge to set up cumulative scores during said time interval.

16. In an amusement device of the character described, the combination with a normally inoperative pistol constructed and arranged to direct a space charge an indeterminate number of times to affect a target in accordance with the skill of the operator during a predetermined limited time interval, of coin controlled means to make said pistol operative, means for limiting the time of pistol operation, automatic means controlled by said target when affected by said space charge to set up cumulative numerical scores during said time interval, and automatically operable means to reset said scoring means at the termination of said time interval.
